UNITED STATES PATENT OFFICE.

LOUIS MADAS, OF NEW YORK, N. Y., ASSIGNOR TO RAPID ENVELOPE SEALING CO., OF NEW YORK, N. Y., A CORPORATION OF NEW YORK.

MACHINE FOR SEALING ENVELOPS.

SPECIFICATION forming part of Letters Patent No. 758,992, dated May 3, 1904.

Application filed April 25, 1903. Serial No. 154,812. (No model.)

To all whom it may concern:

Be it known that I, LOUIS MADAS, a citizen of the Empire of Austria-Hungary, residing in New York, borough of Manhattan, and State 5 of New York, have invented certain new and useful Improvements in Machines for Sealing Envelops, of which the following is a specification.

This invention relates to improvements in envelop-sealing machines of that class in which a number of envelops are placed in a pile into a receiving-box and fed one after the other in a positive and reliable manner to moistening and sealing devices, the object of the invention being to provide means whereby one envelop after the other is engaged singly and moved away from the lower end of the pile, then moistened at the sealing-flap and subjected to pressure so as to be sealed, the envelop receiving box being of sufficient size so as to be adapted to receive envelops of different sizes; and for this purpose the invention consists of an envelop-sealing machine which comprises an envelop-receiving box, a reciprocating moistening and feeding plate at the lower part of the receiving-box, and sealing and presser rollers in line with said plate; said moistening and feeding plate forming the bottom of the receiving-box and being adapted 30 to convey the envelops successively from said box to the sealing and presser rollers.

The invention consists, further, of certain improvements in the moistening device by which the moisture is supplied to the inclined 35 front lip of the reciprocating feeding and moistening plate and from the same to the gummed sealing-flap of the envelop, said feeding and moistening plate being guided by suitable rollers arranged at the sides of the 40 moistening device, so as not to subject the wick of the moistening device to excessive use or to-and-fro bending during the reciprocation of the moistening-plate.

The invention consists, further, of means 45 for adjusting the partition in the receiving-box to different sizes of envelops; and the invention consists, lastly, of certain details of construction and combinations of parts, as

will be fully described hereinafter and finally pointed out in the claims.

In the accompanying drawings, Figure 1 represents a side elevation of my improved machine for sealing envelops. Fig. 2 is a plan view of Fig. 1, showing a part of the receiving-box with parts thereof broken away. Fig. 3 is a vertical longitudinal section on line 3-3, Fig. 2. Fig. 4 is a vertical transverse section on line 4-4, Fig. 3. Fig. 5 is a like section on line 5-5, Fig. 3, shown in the direction of the arrows. Fig. 6 is a vertical longitudinal section through the feeding, moistening, and sealing devices drawn on a larger scale and showing the reciprocating feeding and moistening plate in forward position for delivering an envelop to the sealing and presser rollers; and Fig. 7 is a detail perspective view of the guide-block for conducting the envelop to the sealing and presser rollers.

Similar letters of reference indicate corresponding parts.

Referring to the drawings, A represents the side standards, and B the receiving-box, of my improved envelop-sealing machine, which box is open at its top and bottom. The standards A are secured together by transverse brace-rods 75 A', the receiving-box being supported on said standards and secured thereto in any suitable manner. The standards A are provided at their front portions with extensions A², in which are mounted two pairs of rollers, a pair 80 of sealing-rollers C and a pair of presser-rollers C', both pairs of rollers being rubber-covered, the upper sealing-roller C being yieldingly journaled in guide-blocks g, that are adapted to move in vertical ways g' of 85 said extensions A² under the control of helical springs g', while the lower presser-roller C is supported in bearings of pivoted and spring-actuated arms C², as shown clearly in Figs. 1 and 3.

Along the upper edges of the side standards A, at the interior of the same, are arranged horizontal guideways a, on which the side edges of a reciprocating plate D are guided. Reciprocating motion is imparted to the plate 95 D by cranks D', which are keyed to the shaft

C⁴ of the upper presser-roller C', said cranks being connected by pivot-rods D² with a transverse shaft D³, that is supported in perforated lugs d³ at the under side of the plate D, so 5 that by the turning of a crank-handle D⁴, attached to one of the cranks D', the plate D is moved alternately forward and backward in its guideways.

The front end of the reciprocating plate D 10 is provided with an upwardly-inclined tapering lip d, that is adapted to engage the sealing-flap of the envelop and carry the same forward to the sealing-rollers C. The under side of the reciprocating plate D is moved 15 over the moistening device F, which consists of moistening-wicks f, that extend between rollers f', which are adjusted on their axes in the end walls of a moistening-trough F'. The trough F' extends transversely between 20 the side standards A A, below the reciprocating plate D, and is guided by end pins f² in grooves f³ of the side standards A, the troughs being supported by flat cushioning-springs f⁴ at its under side, as shown in Figs. 3 and 4. 25 The trough F' is supplied from time to time with water by means of a supply-tube f⁵, having a funnel-shaped enlargement f⁶. The upwardly-inclined lip d of the reciprocating plate D is guided in such a manner that it will 30 positively enter between the body and sealing-flap of the lowest envelop of a pile placed in the receiving-box B, said lip engaging the fold of the envelop and feeding the same forward to the sealing-rollers C. The pile of 35 envelops placed in the receiving-box is supported on a forwardly-extending stationary lip b' at the lower end of a transverse partition B', said partition being slightly inclined, and on a tapering lip b² of a guide-block b^x, 40 located in the recessed lower part of the front wall of the receiving-box B, said envelops being supported on said lips b' b² in inclined position, with the face of the envelop upward and the flap of the lowermost envelop hanging 45 downwardly, so as to be reliably taken up by the lip of the reciprocating plate D during the forward motion of the same.

In the recessed lower part of the front wall of the envelop-receiving box B is arranged a 50 keeper b, which is guided on strips b³ of the side walls of the box and moves freely up and down in the same. The keeper b is provided at its lower edge with yielding wipers b⁴. Below the keeper b is arranged the tapering 55 point b⁵ of the spring-cushioned guide-block b^x, which is provided at its inner side with the backwardly-extending supporting-lip b², before referred to, and at the opposite side with a shoulder b⁶, said lip and shoulder being 60 separated from the tapering center point b⁵ by means of slotted openings b⁷, through which any surplus moisture may be readily conducted from the tapering center point onto a receptacle R, supported at the lower 65 part of the machine between the side stand-

ards, as shown clearly in Fig. 3. The guide-block b^x is cushioned by means of helical springs b⁸, the upper ends of which are applied to suitable pins at the under side of the guide-block b^x, while the lower ends of the springs are supported in pins or lugs of inwardly-projecting brackets b⁹, as shown clearly in Fig. 5. By this arrangement the guide-block is capable of yielding to the pressure of the reciprocating plate D when the same is 70 passed forward between the yielding wipers b⁴ and the tapering point b⁵ when delivering an envelop to the sealing-rollers C.

The shaft of the upper presser-roller C' is provided with a gear-wheel H, that meshes 80 with a gear-wheel h on the shaft of the lower sealing-roller C, so as to impart rotary motion to the same. Intermediate gear-wheels h' h² h³ h⁴ transmit rotary motion to the yielding upper sealing-roller C, so that the 85 envelops fed to the sealing-rollers by the reciprocating plate D are taken up by the sealing-rollers and moved forward on the return of the reciprocating plate D. The shaft of the transmitting gear-wheel h' is connected by a 90 pivot-strap h^x with the shaft of the gear-wheel h², the shaft of the latter with the shaft of the gear-wheel h³ by a strap h⁵, and the shaft of the gear-wheel h³ with the shaft of the gear-wheel h⁴ by a pivot-strap h⁶. The intermediate 95 gear-wheels and the connecting pivot-straps permit the upper sealing-roller C to yield while being rotated during the passage of an envelop. Simultaneously with the rotation of the sealing and presser rollers the 100 reciprocating motion of the plate D takes place by means of the pivot-rods connecting the crank on the upper presser-roller C' with the plate D, by which also the feeding and moistening of the envelop is accomplished. 105

The wicks of the moistening-trough are pressed together at their upper ends by means of parallel rollers f' (shown in Figs. 2 and 6) at both sides of said wicks and journaled in slots f⁹ in the end walls of the trough F'. (Shown most clearly in Fig. 2.) One of the rollers f' is provided with socket-holes f⁸ for permitting the convenient axial adjustment of said rollers by means of a small lever to be inserted therein in the well-known manner, 115 so as to adjust the position of the moistening-wicks from time to time when the same are spread apart at their upper ends and produce the reliable moistening of the under side of the inclined lip of the reciprocating plate D. 120 Any other suitable adjusting means than those described may also be used. At each end of the moistening-trough F' and of the spring-cushioned guide-block b^x are arranged rollers r, which are movable therewith and which 125 serve to carry the body of the reciprocating plate D during the forward and backward motion of the same, so as to prevent the wick from being subjected to excessive wear, which would result, were the rollers not present, by 130

the repeated hammering of the corner d^{13} of the moistening-plate, formed by the plate proper and the lip d , or from the to-and-fro bending of the wick during the reciprocation of the plate D.

The envelop-receiving box B is provided at its top with outwardly-extending lugs B^2 , which rest on the standards A, and in its side walls with a number of parallel grooves m , the partition-plate B' being provided with corresponding tongues m' in its ends, so that it can be readily removed and replaced in any one of the parallel guide-grooves, according to the size of the envelops to be sealed. The envelop-receiving box is attached by means of screws to the side standards A, as shown in Fig. 1.

The operation of the envelop-sealing machine is as follows: The partition B' of the envelop-receiving box B is first adjusted to the size of the envelops to be sealed. The envelops are then taken up in suitable quantity and placed in the box in a pile with their sealing-flaps downward and their flap edges or folds against the front wall of the box resting on the lips of the partition and guide-block b^x . The reciprocating plate D serves as a bottom for the receiving-box and is moved in forward and backward direction by the action of the crank-handle and connecting-rod. During the rearward stroke of the reciprocating plate D the receiving-box is bottomless for about one-half its width, so as to permit the flap of the envelop to project slightly into the opening into the bottom of the box. The limit of the forward motion of the reciprocating plate D coincides with the contact of the sealing-rollers C, as shown in Fig. 6. The reciprocating plate D is moved from its rearward position forward, so that its front lip passes in between the body and the sealing-flap of the envelop until it engages the fold of the same, carrying the envelop forward between the yielding keeper and the tapering point of the guide-block, the latter pressing the flap of the envelop into contact with the under side of the lip of the reciprocating plate, so as to moisten the gummed surface of the flap. The reciprocating plate continues then its forward motion until it places the envelop between the sealing-rollers. The reciprocating plate is then returned upon its rearward stroke, while the envelop is taken up and passed through between the sealing-rollers, so as to be sealed and then delivered to the presser-rollers, so as to impart the final closing-pressure and smoothing to the envelop and its contents. The next envelop is then moistened and sealed in the same manner, and so on until all envelops in the receiving-box are sealed, when a new pile is placed into the same. The reciprocating plate performs the function of engaging the envelops and then feeding them forward to the sealing and presser rollers, which receive the envelop,

yielding to the thickness thereof and sealing the same as it is passed between them. The keeper, with its wipers, and the guide-block, with its tapering point below the wipers, prevent any possibility of feeding more than one envelop at a time from the pile, as they hold back all the envelops above the lowest one, while the lowermost envelop is taken up and fed by the reciprocating plate to the sealing and presser rollers. Any small surplus moisture is drained off through the slots at both sides of the tapering central point of the guide-block into the receptacle R, so as to prevent the moistening of the envelops as they are successively moistened and sealed during their passage through the moistening and sealing rollers, while the guide-rollers at the opposite ends of the moistening-trough and guide-block serve to keep the reciprocating plate sufficiently in contact with the wick so as to moisten the same, preventing, however, the wick from being subjected to excessive wear, which would result from too close and sudden a contact of the plate with the wick.

I do not desire to claim in this application anything which has been claimed in my prior pending application for an improved machine for sealing envelops, Serial No. 145,601, filed February 28, 1903, to which reference is made herewith. The new features of the present application are, first, the dispensing with the cloth covering at the under side of the reciprocating plate; second, the arrangement of the moistening-trough with its moistening-wicks, which dispenses with a separate water-tank; third, the guide-rollers for the reciprocating plate, by which the latter is carried over the moistening-wick so as to be in contact therewith and yet prevent excessive wear of the wick; fourth, the arrangement of the wipers and guide-block for holding back the pile of envelops above the lowermost envelop and for drawing off the excess of moisture, and, lastly, the arrangement of the lips on the partition and guide-block for supporting the envelops independently of the reciprocating plate.

Having thus described my invention, I claim as new and desire to secure by Letters Patent.—

1. The combination, with an envelop-receiving box, of a reciprocating envelop feeding and moistening plate forming the bottom therefor, a spring-cushioned moistening-trough arranged below the reciprocating plate, moistening-wicks supported in said moistening-trough, means for adjusting the upper ends of said moistening-wicks relatively to the reciprocating plate, and rollers for sealing the flaps of the envelops, substantially as set forth.

2. In an envelop-sealing machine, the combination of an envelop-receiving box, a reciprocating envelop feeding and moistening plate, a spring-cushioned moistening-trough arranged below said reciprocating plate, moistening-wicks in said trough, means for adjust-

ing said moistening-wicks relatively to said reciprocating plate, and guide-rollers at the ends of said moistening-trough for guiding the body of the reciprocating plate in its reciprocating motion over the moistening-wicks, substantially as set forth.

3. In an envelop-sealing machine, the combination of an envelop-receiving box having a transverse recess at the lower part of its front wall, a yielding keeper in said recess, a yielding guide-block provided with a tapering point located below said keeper, a reciprocating envelop feeding and moistening plate adapted to pass between said keeper and tapering point and rollers for sealing the flaps of the envelops, substantially as set forth.

4. In an envelop-sealing machine, the combination of an envelop-receiving box having a transverse recess at the lower part of its front wall, a yielding keeper in said recess, a yielding guide-block provided with a tapering point located below said keeper, a reciprocating envelop feeding and moistening plate adapted to pass between said keeper and tapering point, a moistening device below the reciprocating plate, and guide-rollers at the ends of the guide-block for guiding the body of the reciprocating plate in its forward and backward motion over said moistening device, substantially as set forth.

5. In an envelop-sealing machine, the combination of a receiving-box having a recess at the lower part of its front wall, a vertically-movable keeper guided in said recess, a yielding guide-block provided with a tapering point below said keeper, a reciprocating feeding and moistening plate adapted to pass between the keeper and tapering point, a moistening-trough below said reciprocating plate provided with moistening-wicks, and rollers at the ends of the moistening-trough and guide-block for guiding the body of the reciprocating plate in its forward and backward motion over said moistening device, substantially as set forth.

6. In an envelop-sealing machine, the combination of an envelop-receiving box having a transverse recess in the lower part of its front wall, a vertically-movable keeper in said recess, a spring-supported guide-block provided with a tapering point below said keeper, a transverse inwardly-projecting lip below said point, and a reciprocating feeding and moistening plate adapted to enter between said keeper and point, substantially as set forth.

7. In an envelop-sealing machine, the combination of an envelop-receiving box having

a transverse recess in the lower part of its front wall, a vertically-movable keeper in said recess, a spring-supported guide-block provided with a tapering point located below said keeper, and a reciprocating feeding and moistening plate provided with an inclined front lip adapted to pass between said keeper and tapering point for feeding the envelops through the same, substantially as set forth.

8. In an envelop-sealing machine, the combination of a receiving-box having a transverse recess in the lower part of its front wall, a vertically-movable keeper guided in said opening, a spring-supported guide-block below said keeper, said guide-block being provided with a tapering point and slots in said block at both sides of the tapering point, a supporting-lip adjacent to said tapering point, a transverse partition in the receiving-box provided with a lip at its lower end and a reciprocating envelop feeding and moistening plate adapted to receive an envelop and feed it through between the keeper and tapering point, substantially as set forth.

9. In an envelop-sealing machine, the combination of a receiving-box having a transverse recess in the lower part of its front wall, a vertically-movable keeper guided in said opening, a spring-supported guide-block having a tapering point below said keeper and an inwardly-extending supporting-lip adjacent to said tapering point, a transverse partition in the receiving-box provided with a lip at its lower end, a reciprocating and moistening plate adapted to receive the envelop and feed it through between the keeper and tapering point, a spring-actuated moistening device below said reciprocating plate, and rotary sealing and presser rollers, substantially as set forth.

10. In an envelop-sealing machine, an envelop-receiving box provided with parallel guide-grooves in its side walls, and a transverse partition provided with tongues for being inserted into one of said guide-grooves for adjusting the box to different sizes of envelops, said partition being provided at its lower end with a forwardly-extending lip for supporting a pile of envelops placed in the box, substantially as set forth.

In testimony that I claim the foregoing as my invention I have signed my name in presence of two subscribing witnesses.

LOUIS MADAS.
